Primary Examiner — T. Chase Nelson(74) *Attorney, Agent, or Firm* — Andrew F. Young, Esq.;
Lackenbach Siegel, LLP(57) **CLAIM**

The ornamental design for a shoe sole, as shown and described.

DESCRIPTION

FIG. 1 is a front perspective view of a shoe sole in accordance with a first embodiment of the ornamental design;

FIG. 2 is a front elevational view of the shoe sole of FIG. 1; FIG. 3 is a rear elevational view of the shoe sole of FIG. 1; FIG. 4 is a bottom view of the shoe sole of FIG. 1; and,

FIG. 5 is a left side elevation view of the shoe sole of FIG. 1; and, FIG. 6 is a right side elevational view of the shoe sole of FIG. 1.

The views described above depict a right-foot shoe sole. A second embodiment of the design is the left-foot shoe sole, which is a mirror image of the views of the first embodiment. The broken line showing of the shoe upper and shoe sole portions and tread portions in dashed lines is for illustrative purposes only and depicts portions and environmental structure that form no part of the claimed design.
